UNITED STATES PATENT OFFICE.

VICTOR A. SVENSSON, OF BROOKLYN, NEW YORK, ASSIGNOR TO AKTIEBOLAGET SVENSKA KULLAGERFABRIKEN, OF GOTTERBORG, SWEDEN, A CORPORATION OF SWEDEN.

MEANS FOR GRINDING THE MANTLE SURFACES OF ROLLERS HAVING ARC-SHAPED GENERATRICES.

Application filed October 8, 1920. Serial No. 415,518.

To all whom it may concern:

Be it known that I, VICTOR ABRAHAM SVENSSON, a subject of the King of Sweden, residing at the city of New York, borough 5 of Brooklyn, county of Kings, and State of New York, have invented certain new and useful Improved Means for Grinding the Mantle Surfaces of Rollers Having Arc-Shaped Generatrices, of which the following 10 is a specification, reference being had therein to the accompanying drawing.

This invention relates to an improved means for grinding the mantle surfaces of rollers having arc-shaped generatrix the centre of which does not coincide with the centre of the roller and is especially adapted for grinding large rollers for roller bearings having spherical outer race.

The object of the invention is to provide 20 mechanism by means of which it will be possible to manufacture rollers the generatrix of which is an exact arc of a circle independently of the wear of the grinding disc.

25 The invention consists, chiefly, in this that the grinding operation is performed by means of a grinding disc having spherical or substantially spherical working surface and that the roller during the grinding operation 30 is rotated about its own axis and at the same time is brought to swing about an axis which passes through the centre of the working surface of the grinding disc and forms an angle with axis of the latter.

35 In the accompanying drawing I have illustrated one embodiment of my invention. Fig. 1 shows diagrammatically a sectional view of the roller and the grinding disc. Fig. 2 is a section on the line A—B in Fig. 1. 40 Fig. 3 is a plan view showing how the parts in Figs. 1 and 2 are mounted and operated.

Referring to Figs. 1 and 2, 1 is the grinding disc which is secured to a rotatable shaft 2 and has a concavely spherical working surface having its centre in 0 and the radius R. The roller 3 to be ground in such manner that its generatrix obtains the shape of an exact arc of a circle with the radius R is brought to rotate during the grinding operation 45 about its own axis 6 and at the same time to swing about an axis through the centre 0, for instance an axis 5—0 parallel with the axis 6. The roller is for that pur-

pose mounted in a suitable carrier shown in Fig. 3 and described later on, which can 55 perform said two movements in relation to the grinding disc. The rotation of the roller about the axis 6 should preferably take place with an essentially greater speed than the movement about the axis 5—0 the 60 result being that each point of the mantle surface of the roller will come into contact with the working surface of the grinding disc several times for each swinging movement about the axis 5—0. The said swinging 65 movement can either be an oscillatory movement between the two limits in which the roller loses its contact with the grinding disc or be a continuous rotation about the axis 5—0 in constant direction. By the 70 said combined movements of the roller in relation to the axis of the grinding disc it is assured that every point of a generatrix of the roller always come into contact with different points of the working surface of 75 the grinding disc, the result being that the latter is worn absolutely uniformly and always maintains an exactly spherical form and the generatrix of the mantle surface of the roller obtains the desired shape of an 80 exact arc of a circle having the radius R.

As the grinding disc is worn it is fed 85 towards the point 0 by means of any well-known automatic feeding device in such manner that its working surface maintains a constant distance from said centre.

In Fig. 3 I have illustrated how the grinding disc and roller are mounted in the proper relation to each other, and have illustrated means for rotating the grinding disc and 90 roller and swinging the latter, in carrying out my method. In this figure it will be seen that the shaft 2 carrying the grinding disc, is mounted for rotation in a bearing 7 on a base or bed 8, and has fixed to it a 95 pulley 9 for driving the shaft. The roller 3 is mounted in a holder consisting of a yoke 11 having a handle 12 for swinging it. The roller is held on its geometrical axis 6—6 between a fixed center stud 13 100 on the yoke and a retractable center stud 14 mounted for endwise movement on the yoke and pressed against the roller by a spring 15 housed in a cavity in the yoke and bearing against the latter and a shoulder on 105 the stud, whereby the stud 14 may be moved

outwardly against the force of the spring to disengage the roller so as to permit the same to be removed and a new one set in its place. The stem of the stud 14 is extended outwardly through the yoke and has connected with it a flexible driving shaft 16 driven from a suitable source of power, the form and character of the engaging surfaces of the stud and roller being such that the 10 rotary motion of the stud 14 by the flexible shaft will, in connection with the engagement of the roller with the rotary grinding surface at the relative angles shown, bring about a rotation of the roller on its geometrical axis. To one side of the axis 6—6 the yoke is formed with hubs 17, 17 provided with aligned bearing cavities 18, 18 in which extend pivoted studs 19, 19 projecting inwardly from standards 20, 20 rising from 15 the base 8, by which means the yoke is swingingly mounted on the axis 5—5 and which extends parallel to the geometrical axis of the roller and passes through the center 0 of the spherical face of the grinding 20 disc.

In the operation of the parts so mounted, the shaft 2 and flexible shaft 16 being rotated, the roller 3 will be rotated about its geometrical axis 6—6, and during this action the operator grasps the handle 10 of the yoke and swings the same back and 25

forth on the axis 5—5, with the result that by the combined operations, every point of a generatrix of the roller will come into contact with different points of the working surface of the grinding disc, and the grinding disc will be worn uniformly and will always maintain an exactly spherical form, and the generatrix of the mantle surface of the roller will be given the shape of an exact arc of a circle having the radius R. 40

Fig. 3 above described illustrates one form by way of example of the mounting and operation of the parts, but it is manifest that other forms of mounting may be adopted without departing from the spirit of the invention. 45

What I claim is:

In a mechanism of the type described, the combination of a rotary grinder having a 50 grinding surface constituting a portion of a sphere, a pivoted holder having centers for rotatably supporting a workpiece, such as a roller, the pivots of the holder lying in a line parallel to the axial line of said centers 55 and being intersected by the axis of rotation of the grinder, and means for swinging the holder on its pivot.

In testimony whereof I have signed my name.

VICTOR A. SVENSSON.
